(54) BALANCE

(76) Inventor: **Jirah Vaughn**

*James Daugherty
of New Haven*

The defendant refers to his three former Patents and making good of the same containing a description of the bars of the said James Daugherty Yang has himself of his Improvement No. the Sliding and Slanting Balance.

To all to whom these presents shall come. Be it known that I, James Daugherty of New Haven in the County of New Haven and State of Connecticut have invented a new and useful improvement in the steel yard or Roman Balance, and that the following is a full and exact description thereof, viz. A steel bar 18 inches in length containing the Kirk on the length of 17 inches by long setting in a straight line 20ths of an inch thick is prepared of the following widths: that is to say, the short arm of the bar is made 48 inches long and 3 inches wide being swelled at one end where the fulcrum is 24 inches. The fulcrum being 24 inches and made fast at the distance of 378 inches from the end of the short arm before the cap is put on, then commencing at the distance of 5 sixteenths of an inch from the point of the fulcrum, a slit is made on an inch wide and through the short arm to receive the sliding pivot, hereafter described. The sides of this slit are so filed as to receive the barre. Then a steel cast iron of threaded steel made equally to fit in the slit and into which the sliding pivot is fastened. On this pivot the cap is hung to which the scale, right hand suspended, certaining the weight. A cap of 20ths of an inch wide is set on with a slot cast in the fore end of the short arm and is made fast, with a single screw running through, into each slit, which connects the head of the cap. In the head of the cap and through the cap a mortise is made 18 inches long and 10th of an inch wide, through which a thin bar or arm of the same width and thickness and about 10 inches long, with a small knob on the end may which serves as a handle, is passed up to and made fast in another slot made certaining the head of the sliding pivot by a pin on which it has a slight sliding motion. Through the cap, in the fore end of the mortise, at right angles with it, a small slot of 10th of an inch square is made and made fast where the end

upon the thin bar, or yoke, which is attached at just one end to the bar of the sliding pivot, and on the lower edge or side of which bar are fastened two rings made equally to fit on the cast iron so as to maintain the sliding at the several points in position below of the yoke. On the upper side of the yoke another yoke is in like manner made fast with a small screw, the point of which yoke acts upon and keeps down the small bar upon the rest. When the sliding pivot, by means of this small bar, is drawn out so that it permits, and those of the yoke which are 3 $\frac{1}{4}$ in. the one against the other, a balance is then adjusted to its lowest point. Owing to the point of the pivot and yoke now opposite to the distance of 17 $\frac{1}{4}$ in. it is obvious when the small bar will be out of its notch on the rest. The balance is now prepared to exert its second power. When lastly, but the yoke is moved up to this intermediate position 2 $\frac{1}{4}$ of an inch, the balance will be prepared to exert its highest power, as will be more fully explained hereafter in describing the graduated physical scales. The long arm of the bar or balance is made 15 in. inches in width throughout, excepting a knot on the upper and under sides at the extreme ends of each square inch, to which the yoke is secured by two ends. The lower knot being produced in the body of the bar and slightly bent back to a yoke point, serving to hold in place that end of the bar in a sleeve let down from a frame above, 18 in. by 14 in. of one inch is then cut through the sleeve to a point within 1 $\frac{1}{4}$ of an inch of the end. The other slit again is made 18 in. wide and 1 $\frac{1}{4}$ of an inch wide except from a point of an inch from the fulcrum and throughout the length of the arm. As to this point and equally fitting, it is placed the graduated scale which is made to slide back and forth this is and is maintained in the yoke by the following means: a small strip of paper throughout right angles, near the end of the scale near the fulcrum of sufficient length on one side to hold a portion of the pivot, and on the other side to pass through the slit in the long arm into a knot on the second side, which maintains that end of the scale on the yoke on the end of the long arm on the knot above mentioned. A thin and narrow strip of steel having a weight that end of the scale is made fast to the knots and is denominated the ring, which maintains the other end of the scale in the yoke.

and also prevents its being drawn quite out from the bar. The scale to be graduated as hereof is divided being made to fit the above mentioned frame is 13 1/2 the scale is bright and weighs 11 1/2 ounces avoirdupois, on the end over the fulcrum a portion of the frame somewhat the heaviest is attached by the lower holding the nut on the reverse side of the bar. The portion of the frame weighs 16 1/2 ounces avoirdupois. On the other end of the scale there is fixed a small of an inclined plane 30° and 45° in length upon which is placed another portion of the frame left there the frame was weighing 9 1/2 ounces avoirdupois. This portion is necessary to balance the balance frame and serves the additional office of putting the bar in balance in weighing. The scale is then divided into three longitudinal divisions a compartment of which is marked the three equal parts of the balance. Being placed on the ground on the bar and close up to the fulcrum as near as may be the scale is then ready for graduation, which is accomplished after this manner. suspend the bar horizontally by the loop on the fulcrum, letting the bar rest in the inclined plane from the frame. Draw out the sliding spirit level to points and those of the fulcrum will be 3 1/2 inches apart, turn the balance frame on or off the middle scale as the case may require so that the line of the bar be in equilibrium; then draw a line across the scale close to the right-hand side of the frame where this first line will intersect 0 on the upper horizontal division in the bar in balance. When the bar is in balance at this point it will be accurate in weighing on the higher part. Next suspend a pound weight on the bar as placed from under and from the loop on the sliding spirit level out the scale from left to right until the bar is again in balance and across the scale as before and this second transverse line will mark the weight of 1 pound in the upper longitudinal division on the scale. Then, as before another 1 pound weight on the bar, draw out the scale again to a balance, mark another line across and the mark or graduation for 2 pounds is also divided. Proceed on like manner until the graduation are complete to the left-hand end of the scale. Again turn up the sliding spirit level a point 1/2 the inches from the point of the fulcrum where the small bar will catch by the nut on the scale. ^{etc.}

the scale at O , marked on the upper division, the second arm will divide in with three divisions, immediately under O , 135 pounds. The graduation in the division will coincide with those in the upper, and increase by 3 pounds, a corresponding transverse line to the ultimate power of the division, lastly, lifting up the sliding point to cause the platform to its next position which is 90, the other end being between the points; place the scale again at the mark O , on the upper division, the under will divide directly under on the lower division 300 pounds. The graduation in this lower division also coincide with those in the two upper ones, and increase by four pounds at every successive transverse line to the ultimate power of the division which is 910 pounds. After the same manner are increased all other measures of weight heavier and in commercial as other bodies of transverse graduation on this scale. It is obvious that by reducing the weight of the platform proportionately, smaller and smaller divisions of the pound may be graduated, but in that case the capacity of the balance will be relatively diminished, as like manner. By increasing the force an increased capacity is given to the balance to any extent. In the long arm of the bar and the scale may be extended, and smaller and smaller divisions graduated without reducing the power. I contemplate applying this compound balance to the weighing of all ponderable bodies both great and small and in consideration of the machines having organs always to the end to which the instrument is to be applied, and therefore giving it a greater proportion according to those cases, in order to give it strength. It may be used with the common scale or when the platform or in any other way, and manner, used with other balances for holding the weight, always observing that when one becomes the beam, it has the least weight placed in equilibrium at the point O , on the upper division, in order to ascertain that no smaller beam is accommodated on the platform, to distract the balance or get it out of tune. What platform as improvement and not previously known in the above described machine is first the combination and application of the graduated plane, scale with the point and index as above described, to the long arm of the steelyard and applied to the surfaces of weighing bodies. In this sliding proportion, the

the short arms of the steel yard are also adjustable, and opposite either
with or without the said combined graduated plane scales, a glass case
is being arranged of all practicable substances, so as to inclose
the above as a true specification of my said invention and improvement.
I have herewith also annexed my drawing of the day of effect in the year
of our Lord one thousand eight hundred and thirty six.
